UNITED STATES PATENT OFFICE

170,029

PENCIL SHARPENER AND THE LIKE

Harry O. Sandberg, Boston, Mass.

Application December 22, 1952, Serial No. 22,804

Term of patent 3½ years

(Cl. D74—21)

To all whom it may concern:

Be it known that I, Harry O. Sandberg, a citizen of the United States, residing at Boston, Massachusetts, have invented a new, original, and ornamental Design for a Pencil Sharpener and the like, of which the following is a specification, reference being had to the accompanying drawing, forming a part hereof.

Fig. 1 is an end elevation of a pencil sharpener, showing my new design;

Fig. 2 is a side elevation thereof;

Fig. 3 is a front elevation; and

Fig. 4 is a perspective view of the said pencil sharpener as it appears in open position.

What is claimed is:

The ornamental design for a pencil sharpener and the like, substantially as shown.

HARRY O. SANDBERG.
